UNITED STATES PATENT OFFICE.

FRANK BYCROFT KEALL, OF LEICESTER, ENGLAND, ASSIGNOR TO UNITED SHOE MACHINERY CORPORATION, OF PATERSON, NEW JERSEY, A CORPORATION OF NEW JERSEY.

EDGE-SETTING MACHINE.

Application filed July 9, 1920. Serial No. 394,324.

To all whom it may concern:

Be it known that I, FRANK BYCROFT KEALL, a subject of the King of England, and residing at Leicester, Leicestershire, England, have invented certain Improvements in Edge-Setting Machines, of which the following description, in connection with the accompanying drawings, is a specification, like reference characters on the drawings indicating like parts in the several figures.

This invention relates to control mechanism, and more especially to automatic machinery wherein the relative movement of the work and a tool is controlled automatically as by hydraulic valve mechanism.

The invention will be disclosed as embodied in the edge setting machine disclosed in United States Letters Patent No. 1,078,684, granted on the application of Keall, Gouldbourn, and Jerram, but is not to be considered as limited in its application to an edge setting machine, or, indeed, to machines for operating upon boots and shoes, except as so limited in the claims.

Machines of the general character to which this invention is peculiarly adapted comprise a tool and a work support arranged for relative movement (preferably automatic) to cause the point of operation of the tool to be transferred along the work, and a controlling mechanism which acts during the transfer to control or correct automatically as, for example, by feelers, the relative positions of the tool and work in accordance with changes in their relations due to the progress of the operation. The controlling mechanism may comprise gages, feelers, or other contact members, and in the machine shown, is operated by feelers bearing directly upon the work, but it may co-operate with any form or contour or pattern surface having a desired definite relation to the work. In the machine shown this correcting mechanism comprises a hydraulic piston, the movement of which effects the corrective movements desired, and a main valve controlling the piston, the main valve being operated through a work or pattern contact control, and a relay valve

operated by it. This relay valve mechanism is not claimed herein, being a joint invention of myself and Arthur Ernest Jerram, and claimed in an application Ser. No. 390,146, filed June 19, 1920. 55

When the control means is disengaged from the work, in machines of this type (as is the case when the work is finished, and the tool is retracted in order to remove it from the machine), the tool and work holder 60 are liable to be moved into abnormal positions. In machines having hydraulic control it is impossible, as a practical matter, to construct the hydraulic control mechanism so accurately as to be absolutely free 65 from leakage, the result being that when the machine is standing inoperative, the jack correcting mechanism and the tool head correcting mechanism tend to move into one or the other of their limiting positions. 70 This makes it difficult to insert and begin operation upon a new piece of work. A mechanism for bringing the tool head to normal position under these circumstances which has been successful is a subject-mat- 75

ter of Patent No. 1,006,484, granted upon the application of Keall and Gouldbourn. Prior to the invention of the relay valve control mechanism above mentioned, it was customary to swing the jack into operative position as it was being presented to the tool, by a handle which controlled a normally feeler-operated shaft, and thereby operated the jack correcting mechanism. The friction in the massive jack parts caused a tolerably smooth response to the action of the handle, but on the application of the feeler actuated relay valve mechanism above mentioned, the sensitiveness became so great that it was difficult to hold the jack in any 80 definite position, and it jumped to and fro. This caused much trouble, since if the sole edge face is not normal to the line of advance of the tool head as it approaches the work, one of the feelers which engage underneath the sole will engage under the sole before the other, and the tool head will be tipped out of proper position. 85

It is an important object of the present invention to insure the return of the work 90

holder to a predetermined normal relative position under such circumstances. This is done by automatically moving the control valve by means of the undesired movement itself in such a sense as to correct the movement so that the jack is held balanced in the desired path along which it is desired to have the tool operate. In the machine shown, a member moving with the jack correcting structure supplementarily controls the main valve by means of a cam, so that movement away from the desired position will move the valve in such a manner as to correct the undesired movement. The piston valve may be set to leak a substantial amount in one direction so that the main correcting piston will tend to move to corresponding extreme position with its operated parts. These moving parts, through the cam mechanism, move the valve stem so as to throttle, offset, or equalize the leakage when the parts reach a certain predetermined position, and means is provided to move the cam out of controlling position as an incident of the commencement of operation on a work piece.

These and other features of the invention comprising certain combinations and arrangements of parts will be understood from the following description of a preferred embodiment thereof selected for purposes of illustration and shown in the accompanying drawings in which,

Fig. 1 is a front elevation of the machine with a part of the frame broken away to show the internal construction.

Fig. 2 is a plan view of the machine shown in Fig. 1 with the upper part removed.

Fig. 3 is a side view of a portion of the machine shown in Fig. 1 drawn to a larger scale, with certain parts in section.

Fig. 4 is a vertical section showing in detail the tool carrying head.

Fig. 5 is a plan, partly in section, of the parts shown in Fig. 4.

Fig. 6 is a front elevation showing certain details of the feeler mechanism.

Figs. 7, 8 and 9 show in three positions the valves which control the supply of fluid to the correcting hydraulic cylinders.

Fig. 10 is a perspective of the tool carrying head, and

Fig. 11 shows the mechanism for bringing the jack to normal work inserting position.

Only enough of the machine is described in detail to enable the invention to be understood. For a fuller description of parts not material to the present invention, reference is to be made to Patent No. 1,078,684, above mentioned.

In this specification it is to be understood that by the path of relative traverse of the tool is meant that path in which, during the

relative motion of the tool and work, the tool is in active operation on the work; and it is contemplated that this path may be shorter than the extent of relative movement of the tool and work, since these members may be so controlled as to move clear of each other before the relative motion of tool and work has ceased.

The machine comprises a jack or work support upon which the boot or shoe is securely held and an edge setting tool that has rapid vibratory movements of small amplitude imparted to it to burnish the sole edge of the shoe with which it is maintained in engagement.

The jack comprises a frame 2 of a laterally-disposed U shape on the lower arm of which is a dove-tailed slideway 4 that supports an adjustable block 6 for engaging and positioning the tread face of the sole of the shoe; this block may be adjusted longitudinally of the shoe along the slideway and be retained in its adjusted position by any suitable means such as a spring plunger 8 so located in the frame as to engage suitably shaped recesses in the block 6. Toward the bend of the U-shaped frame there is an adjustable, vertically-disposed rest 10 for the tread face of the heel of the shoe.

A U-shaped clamp 12 adapted to embrace the counter portion of the shoe so as to position it centrally in the jack is adjustably mounted in the bend of the frame.

The shoe is held upon the jack by a pendant clamp member 14 carried in the upper arm of the frame and operated by the handle 20 so as to engage the shoe and hold it firmly in the jack. A more detailed description of this clamp is not necessary to the disclosure of the present invention but it will be found, if desired, in Patent No. 1,078,684, above referred to.

The jack and tool are moved relatively by automatic mechanism to transfer the point of operation of the tool around the sole edge, and mechanism, controlled by feelers bearing upon the sole edge and by feelers bearing upon the tread face of the sole near its edge, imparts the relative angular movements between the shoe and tool that are necessary to insure that the acting face of the tool shall bear evenly upon every part of the sole edge upon which it operates.

The jack 2 is secured upon the end of a vertical spindle 42 journaled in bearings at one end of a frame 44 of which the other end is pivotally carried at 46 (see Fig. 2) upon a second frame 48 that swings about a vertical spindle 50 supported in the machine frame. The two frames 44 and 48 in their mean position are disposed approximately at right angles to each other so as to permit horizontal movements of the jack in any direction.

A lobed cam 52 fixed to the lower end of

the spindle 42 has a cam groove formed in it which engages two rollers 54, 54 which are supported in a manner hereinafter described. The cam and rollers so guide the 5 jack during its movement that the sole edge of the shoe on the jack moves past the tool in a path agreeing approximately in shape with the contour of the sole edge, or in a path that is the mean of a variety of 10 contours of shoe soles; the relative traverse of the tool and sole edge being brought into exact agreement with the contour of the shoe under operation by the horizontal and vertical movements which are imparted 15 to the jack and tool respectively by the feeler mechanism.

The mechanism for driving the jack 2 comprises a slide 56 that is mounted to reciprocate in guideways 58 and 60 attached 20 to or formed upon the machine frame. The slide 56 is coupled by a piston rod 62 to the piston 64 of a hydraulic cylinder 66 secured to the machine. Motion is transmitted from the slide 56 to the jack by means of two 25 chains or other similar flexible members 68 and 70. The chain 68 is secured to the slide 56 at one end and after passing around pulleys 72, 74 and 76 is attached at its other end at 78 to the cam 52; and the chain 70 also secured to the slide 56, passes around 30 pulleys 80, 82, 84, 86, 88, as shown in Figs. 2 and 3, and is joined to the cam at 90. To increase the motion derived from the slide 56 the pulleys 74 and 82 are mounted 35 upon the slide while the remaining pulleys, except 84, are carried upon the machine frame. The pulley 84 is carried upon a lever 92 pivoted to the machine frame and is acted upon by a spring pressed rod 94 to 40 keep the chains 68 and 70 under the necessary tension. If desired, the chains instead of being attached to the cam 52 may be secured to a pulley of corresponding formation.

45 By the connections above described, the jack is oscillated from side to side by the reciprocation of the slide 56 and the direction of motion of the slide is reversed automatically by a mechanism not necessary 50 to be described here, a full description of which will be found in Patent No. 1,078,684, already referred to. This mechanism operates the valve 102 that controls the supply of fluid to both sides of the piston 64 in 55 the hydraulic cylinder 66 before mentioned.

The point of operation of the tool is transferred along the sole edge of the shoe, from the shank on one side of the sole, around the toe portion, to the shank on the other 60 side of the sole; the direction of motion of the jack being reversed when the tool reaches the shank.

65 The edge setting tool 200 has an acting face 202 to engage the sole edge and is provided with a lip to engage the underside

of the sole edge. The upper side of the sole edge preferably is engaged by a stitch wheeling disk 204 that is pivoted upon the tool.

The tool is movably mounted in a holder 206 so that it may turn freely about the 70 center 207 in a vertical plane transverse to the end of the shoe. The shank 208 of the holder 206 is slidingly keyed in a T-shaped piece 210 having a vertically extending stem 211 fulcrumed in a bushing 213 in an extension 212 from a sleeve 214 that is rotatably mounted at 215 in a bearing frame 216 supported by pivots 218 which couple it to two pairs of twin levers 220, 222. The twin levers 220 are pivoted upon a frame lever 80 224 pivoted at 226 upon the machine frame. The twin levers 222 are connected to the frame lever 224 by a bell crank 228 pivoted at 230 to the frame lever 224. The other end of the bell crank lever 228 is coupled 85 to a projection from the machine frame by means of an anchor link 232. By this construction the tool holder 206 can be vibrated laterally about the fulcrum 211 of the T-shaped piece 210; the sleeve 214 and tool 90 holder 206 can be angled about the common axis of the shank 208 and of the sleeve 214; while the sleeve 214, tool holder 206 and bearing frame 216 during their lateral and vertical movements to follow the sole edge 95 are maintained horizontal by the action of the twin links 220, 222 which, in conjunction with the bell crank 228 and link 232 constitute a parallel motion device.

The edge setting tool 200 is vibrated 100 rapidly about the axis of the stem 211 by connections from a shaft 234. This shaft may be oscillated by any suitable mechanism but preferably by a mechanism of the type described in the specification of 105 U. S. Patent No. 1,035,445, granted Aug. 13, 1912. This mechanism is indicated at 236, Fig. 1, and is not herein described as it, in itself, forms no part of the present invention. The mechanism may be conveniently 110 operated from the pulley 348. The shaft 234 is connected with the tool holder 206 by a universal coupling comprising a sleeve 238 open at the top, as at 239 to admit the member 210, the ends of the sleeve being pivoted 115 upon the shank 208 outside the member 210, and a fork 240 that is secured to the shaft 234 and is pivotally connected with the sleeve 238 by a pin 241 disposed at right angles to the shank of the tool holder. The 120 member 238 constitutes the cross-shaped member of the universal joint between the shaft 234 and the stem 211.

Backward thrust of the tool owing to its pressure upon the work is transmitted to 125 the bearing frame 216 by a thrust rod 242 seated at one end against a set screw 244 screwed into the frame 216, its other end engaging the bottom of a recess in the shank of the tool holder 208, the point of engage- 130

ment being located at a point in the axis of the T-shaped piece 210.

The tool 200 is pressed against the sole edge of the shoe by means of a spring 246; 5 and by the co-operation of this spring with the cam 52 on the lower end of the spindle 42 of the jack 2 the point of operation of the tool is caused to travel along the sole edge during the movement of the jack. But 10 it is necessary during the movement of the jack that there be angular movement in a horizontal plane between the jack and the tool to maintain always the acting face of the tool in proper engagement with the sole 15 edge at every part of the contour thereof. Further, it is necessary also that the jack and tool be turned relatively about an axis that is normal to the acting face 202 of the tool owing to the fact that all parts of the sole do not lie in the same plane. These 20 movements of adjustment between the jack and the tool are effected automatically by the correcting devices hereinafter described.

The correcting device for angling the jack 25 in a horizontal plane in relation to the tool comprises a hydraulic cylinder 248, the piston rod of which is connected by a link to a jack correcting lever 250 pivoted at 252 to the machine frame. This lever supports 30 the two rollers 54, 54 hereinbefore referred to as engaging the groove in the cam 52 on the lower end of the jack spindle. The valve 254 of the hydraulic cylinder is controlled by two feelers 256, 258 which, under 35 the action of suitable springs, bear upon the sole edge, one on each side of the edge setting tool 200. The feeler 256 is coupled to one end of a lever 260 pivoted upon an extension from the sleeve 214 and the feeler 40 258 is coupled to a lever 262 also pivoted upon the sleeve 214. The lower ends of the levers 260, 262 are connected by a cross-bar 264 (see Fig. 6) which constitutes one element of a universal joint connected to the 45 upper end of a shaft 266 having at its lower end a similar joint with the spindle of the valve 254. The operation of this correcting device is as follows:—When the tool is bearing evenly upon the sole edge, the valve 254 of the cylinder is maintained closed by the 50 connections between it and the feelers 256, 258. But when the feelers are moved relatively to one another by changes in the contour or general direction of the sole edge 55 passing the tool, the levers 260, 262 to which the feelers are coupled will likewise be moved relatively, thus angling the cross bar 264 that joins them and transmitting motion by the shaft 266 to the valve 254. 60 The valve being thus actuated causes the piston of the cylinder 248 to be set in motion so that the jack correcting lever 250 is turned upon its pivot 252. The jack 2 being connected to the lever 250 by the 65 rollers 54, 54 and the cam 52 will also be

swung about the pivot 252 of the lever 250 as a center until the sole edge of the shoe on the jack is returned by such movement to the position in which the tool bears evenly upon it, by which time the feelers 256, 258 will likewise be restored by the movement of the sole edge to their initial position and they will close the valve 254 and stop the motion of the piston and of the parts connected therewith. 75

The correcting device that effects a relative turning movement of jack and tool about an axis that is normal to the acting face of the tool comprises a hydraulic cylinder 270 the piston of which is connected by a thrust rod 272 with an extension 274 from a collar that is secured to the projection 212 from the sleeve 214. A spring 276 connects the sleeve 214 and the frame 216 and opposes the thrust of the rod 272. The valve 278 that regulates the admission of fluid to the cylinder 270 is controlled by two feelers 280, 282 that bear upon the tread face of the sole of the shoe immediately adjacent to the sole edge. These feelers are formed as spring sustained levers pivoted upon extensions from the sleeve 214, the free ends of the levers being coupled by a cross bar 284 connected by a universal coupling and a shaft 286, with the rotary valve stem of the cylinder 270. The action of this correcting device is similar to that first mentioned, that is to say, the feelers 280, 282 being displaced relatively by changes in the contour of the portion of the sole engaged by them, angle the cross bar 284 and turn the valve 278 so that the latter is actuated either to cause the piston of the cylinder 270 to be raised by the admission of fluid or to permit it to be depressed by the action of the spring 276 on the sleeve 214. The sleeve, tool holder and tool are thus turned about the axis of the shank of the latter to restore the sole edge and tool to their original relationship, namely one in which the plane of vibration of the tool coincides with that of the part of the sole edge engaged by it. The angling of the sleeve 214 causes the feelers 280, 282 bearing on the sole to be returned to their normal position, thus again actuating the valve 278 and stopping the motion of the piston. 115

It may be here remarked that in order to permit movement of both sets of feelers toward and away from the valves controlled by them as the feelers follow the traverse of the tool, or as the tool carrying head is moved bodily toward and from the work, the shafts 266 and 286 preferably are made telescopic and with pin and slot connections so that turning movements only are transmitted to the valve. The shaft 234 which imparts vibratory movement to the tool is also made telescopic as shown in Fig. 1 130

to permit the movements of the tool hereinbefore indicated.

To move the tool into engagement with the sole edge or to remove it therefrom, a starting and stopping lever or controlling lever 290 is provided which is fixed upon a rockshaft 292 journaled in the machine frame. The rockshaft 292 has upon it an arm 294 to which is pivotally linked a plunger 296 into which extends a rod 298 free to turn within a bearing upon the frame lever 224. The spring 246, the function of which is to keep the tool pressed against the sole edge while the machine is in operation, surrounds the rod 298 and abuts at its lower end against a collar 300 supported by projections from a nut 302 working on a screwed portion of the rod 298 and at its upper end against an abutment 304 pivoted on the lever 224. A collar 306 secured to the upper end of the rod 298 operates to limit the movement of the rod in the abutment 304 under the influence of the spring 246. By this construction the tool can be moved 25 yielding toward the sole edge and removed positively therefrom. Preferably the plunger 296 works in a dash pot 308 which cushions the movement of the lever 290 and frame lever 224 when the machine is thrown automatically out of action.

A pump 360 is provided which supplies fluid under the requisite pressure to the hydraulic cylinders of the machine and there is an air pressure chamber 362 into which the fluid is pumped before passing to the hydraulic cylinders.

The valve mechanism for operating the automatic correcting devices is contained in a casing 370. This casing contains both of the mechanisms for angling the jack in a horizontal plane and rocking the tool about a horizontal axis. A description of the former of these mechanisms will suffice inasmuch as they are quite similar. The casing 370 contains a cylindrical bore 372 enlarged at its bottom as shown at 374 to provide a shoulder 375 and containing the main piston valve 376. This valve is of the balanced or equilibrium type and is reduced as shown at 378, 380, 382, the remaining portions 379, 381, 383, 385 fitting the bore 372 accurately. The lower end of the piston 376 is chambered as at 384 to accommodate a spring 386, one end of which rests against the piston and the other end against a disk 388 in the bore 374. The diameter of this disk is larger than the diameter of the main body of the bore 372 so that it can rest against shoulder 375 at the place where the bore changes size. Below the disk is a spring 392 substantially stiffer than the spring 386, one end of which rests against the disk and the other against the bottom 60 of the casing 370. A pin 394 is fixed in the piston 376 and serves to guide the

springs and the disk, and extends outside the casing for a purpose to be described below. One side of the casing has two ports 396, 398 from which pipes lead to the ends of the cylinder 248 to operate the piston therein. These ports are spaced to contact with the valve portions 381, 383. The other side of the casing has three ports 400, 402, 404. When the piston 376 is in the position shown in Fig. 7, oil from the pump 75 360 enters the port 402, passes around the reduced portion 380 and into the port 396, operating the piston in the cylinder 248. The oil on the other side of the piston in the cylinder exhausts through the port 398 around the reduced portion 382 and out of the port 404 to the pump 360. When the piston 376 is in the position shown in Fig. 9, oil from the pump enters through the port 402, passes around the reduced portion 80 380 and out of the port 398 to operate the piston in the cylinder 248 in the other direction. The oil on the other side of the piston in the cylinder exhausts through the port 396, passes around the reduced portion 378 85 90 and returns to the pump through the port 400. When the main piston is in the position shown in Fig. 8, both ports 396 and 398 are closed and the piston in the controlling cylinder 248 is held motionless. 95

The main valve piston 376 is operated by the following described mechanism. The shaft 266 passes into the casing 370 and carries a lug 406 extending laterally from it. A small dog 408 is pivoted at 410 upon the casing 370 in position to be swung by contact of the lug 406 with one side of it. Its other side engages a small plunger 412 sliding in a guide in the casing 370. This plunger has a reduced end of peculiar formation. The tip end is conical as shown at 414. Behind this conical end is a reduced cylindrical portion 416 which is joined to the main body of the plunger by another conical portion 418. The end is arranged to move in and out of a port 420 in the casing which extends between a chamber 422 leading to an outlet pipe 424 and a recess or pressure chamber 426 formed in the top of the cylindrical bore 372. A very small inlet pipe 428 communicates with this recess, so that the pressure in the chamber depends on the extent of opening of the port 420. 100 105 110 115 120

Suppose the parts are in the Fig. 7 position and that the feelers which control the shaft 266 are operated in such a way as to move the valve piston 376 from this extreme position. The feelers will turn the stem 266 so as to force the plunger 412 to the right in Fig. 7, thereby reducing the effective area of the aperture 420. This causes the pressure in the chamber 426 to increase, as the fluid is pumped in through the inlet pipe 428. When the pressure increases sufficiently 125 130 the piston 376 will move to the right com-

pressing the spring 386 until the end of the piston seats upon the disk 388. At this point the ports 396 and 398 (Fig. 8) will be closed, the cylindrical portion 416 will just be entering the port 420, and the control piston in the cylinder 248 will be locked. It will not yet have begun any reverse movement, but if it was moving at the time the plunger 412 began to move, its movement in that direction will gradually have stopped. Further movement of the piston 376 cannot occur until the pressure in the chamber 426 has increased a substantial amount equivalent to the (substantial) difference in the pressures exerted by the springs 386 and 392. The major part of this increase in pressure will occur after the cylindrical portion 416 of the plunger has passed into the port 420. The purpose of this cylindrical portion is to necessitate an appreciable movement of the feelers in raising the pressure in the chamber 426 to the required degree. The pressure having reached the required point, the disk 388 moves back against the spring 392, compressing it until the parts reach the position shown in Fig. 9 at which time the ports at 396 and 398 will have been uncovered and the oil will pass through them in the direction opposite to that in which it was passing at the beginning of the described cycle, and the correcting movement initiated by the movement of the feelers will take place.

The behavior of the apparatus is quite similar in moving in the opposite direction. As the pressure in the chamber 426 drops, the piston 376 moves to the left in Fig. 9 until the spring 392 has seated the disk 388 on the shoulder 375, and the pressure is then permitted to drop a substantial degree after a substantial movement of the plunger 412, before the piston begins to move again.

The mechanism described, comprising the two springs and the cylindrical portion of the plunger 416 will thus cause a certain slight sluggishness in response to the feeler movement, but will entirely prevent hunting inasmuch as a substantial difference in pressure in the chamber 426, which means a substantial movement of the feelers, is necessary in order to change the control from one phase to the other. The plunger 412 and its operating parts can be made very small and light in weight since the aperture 420 need not be at all large and therefore the response of the plunger to the reaction between the work and the feelers is practically instantaneous. At the same time, the main valve structure, comprising the piston 376 and its related parts, can be made as heavy and rugged as is found necessary, instead of being governed in construction by the force exertable by the feelers which ultimately control it, as would be the case if the feelers operated upon it directly. The force which operates the main piston 376 is the pressure

of springs and the pressure in the chamber 426 and the adjoining part of the bore 372 above the piston. This pressure may be varied by the additional or subtractional flow of a small quantity of fluid and this flow may take place at any desired part of the chamber. Therefore the plunger 412 may be located as conveniently as desired to the feelers while the main valve piston may be located elsewhere in the machine where it will be out of the way. The chamber 426, of course, may be reduced to a small pipe connecting the bore 372 with the aperture 420, all that is necessary being a means of transmitting hydrostatic pressure to the piston 376.

The mechanism for maintaining the jack in convenient position for the insertion of new work will now be described.

On the jack correcting lever 250 is fast an upstanding arm 430 pivoted to which on a horizontal pivot 432 is a second arm 434 having a cam 436 on its upper surface immediately below the lower end of the pin 394. The end of this arm 434 is supported by one end of a lever 438 pivoted between its ends on a horizontal pivot 440 at one end of a vertically disposed bell crank 442 pivoted to the frame of the machine at 444 and the remaining end of which is connected by a third horizontal pivot 446 to one end of a rod 448 the opposite end of which is threaded into a nut 450 held from endwise movement in the frame of the machine and provided with an enlarged knurled head easily accessible to the operator. The other end of the lever 438 is bent downwardly at 452 and held in contact with the frame of the machine by a tension spring 454.

A projection 456 from the lever 438 on the same side of its fulcrum as the downwardly bent end 452 is in the path of a push rod 458 pivotally connected to a crank arm 460 on the starting shaft 292 to rise as the starting lever finishes its travel in the starting operation and moves the lever 438 to allow the arm 434 and its cam surface 436 to fall, (Fig. 7), thereby releasing the piston valve to the control of the relay valve and feelers.

Movement of the jack in that direction in which leakage through the valve system tends to move the jack when the tool head is in inoperative position will be accompanied by corresponding movement of the jack correcting lever 250. The arm 434 will move in company with it and the cam surface 436 is so formed that when moving in such a direction it will act on the pin 394 to move the piston member 376 in a direction to cause movement of the jack in the sense opposite to that in which leakage tends to move it. Consequently these opposing influences establish a balance determining a definite position of the jack not

withstanding leakage, which position may be readily varied by rotation of the knurled head 450 aforementioned which moves the bell crank about its fulcrum and raises or

5 lowers the fulcrum 440 of the lever 438 which it supports and the downwardly bent end 452 of which is definitely positioned by the frame.

The mechanism above described is entirely 10 automatic, independently of leakage in the piston valve, since a position of the jack-correcting lever 250 other than that for which the machine is set will cause a movement of the pin 394 in a direction to move the jack correcting lever 250 back to the normal 15 position. It may, however, be sometimes regarded as desirable to set the valve to leak definitely in one direction (and the apparatus will normally wear into this condition 20 irrespective of manufacturing intent), as for example, by making the cylinders 381, 383 slightly conical in the same direction, say, with the apices of the cones to the right in Fig. 8. The piston 376 would then be shifted to the right in Fig. 8, by the dropping of the pin 394 along the cam 436 until the port 398 barely opened as in Fig. 9 so that the tendency to leak would just be balanced.

25 Having described my invention, what I claim as new and desire to secure by Letters Patent of the United States is:—

1. In a machine of the class described, a work holder, a tool, means for moving the work holder relatively to the tool to transfer the point of operation of the tool along the work, and means, controlled by an abnormal position of the work holder after removal of the work, for returning said work holder to a normal position.

2. In a machine of the class described, a work holder, a tool holder, means for oscillating one of said holders around an axis to transfer the point of operation of the tool along the work, and means operated by movement of said holder from a normal angular position to replace said holder when the work is removed.

3. In a machine of the class described, an angularly movable work holder, a tool, means for angling the work holder relatively to the tool to transfer the point of operation of the tool along the work, and means for insuring the return of said work holder to a predetermined normal position after the removal of the work.

4. In a machine of the class described, a work holder, a tool, means for moving the work holder relatively to the tool to transfer the point of operation of the tool along the work, correcting mechanism for correcting the operation of said means to maintain the tool and work in proper operative relation in accordance with the contour of the work, and means arranged to become opera-

tive upon the disengagement of the work from the holder to return said work holder to a predetermined normal position.

5. In a machine of the class described, a work holder, a tool, means for moving the holder to carry the point of operation of the tool along the work, correcting mechanism for correcting the operation of said means to maintain the tool and holder in proper operative relation at all parts of the work, 70 and a cam movable with the work holder out of normal position to cause reverse movement of the holder and to restore it to a normal position when the work is removed.

6. In a machine of the class described, a work holder, a tool holder, operating means for relatively moving them to carry the point of operation of the tool along the work, a pattern-contact operated correcting mechanism for differentially correcting the 85 operation of said means to maintain the holders in proper operative relation at all parts of the work, and means comprising a cam and connections operated by a substantial movement toward an abnormal position to reverse said movement, whereby the 90 holders are maintained substantially in relative operative position.

7. In a machine of the class described, a work holder, a tool holder, operating 95 means for relatively moving them to carry the point of operation of the tool along the work, a correcting mechanism for differentially affecting the operation of said means, a hydraulic valve for controlling 100 said correcting mechanism, a feeler mechanism for controlling said valve, said valve being constructed and arranged to cause normally a movement of the operating means in one direction, said movement being normally corrected by the feeler mechanism, and means for correcting said movement when the feeler mechanism is inoperative.

8. In a machine of the class described, a work holder, a tool holder, operating 110 means for relatively moving them to carry the point of operation of the tool along the work, a correcting mechanism for differentially affecting the operation of said means, a hydraulic valve for controlling said correcting mechanism, and a cam and connections between the valve and a holder whereby movement of the holder toward abnormal position operates the valve to correct said movement.

9. In a machine of the class described, a work holder, a tool holder, means for relatively moving them to carry the point of operation of the tool along the work, said means being constructed and arranged to 115 carry one of the holders to inoperative position when work and tool are not in contact, and means operated by motion of the holder toward said inoperative position to return said holder to operative position, 120 125 130

whereby said holder is maintained at approximately operative position, said means being automatically thrown out of operation by the starting mechanism of the machine.

5 10. In a machine of the class described, a work holder, a tool holder, operating means for relatively moving them to carry the point of operation of the tool along the work, a feeler operated correcting mechanism for differentially correcting the operation of said means to maintain the holders in proper operative relation at all parts of the work, and means comprising a cam and connections operated by a substantial movement toward abnormal position to reverse said movement, whereby the holders are maintained substantially in relative operative position, said connections being automatically broken by the act of starting the machine.

10 11. In a machine of the class described, a work holder, a tool holder, operating means for relatively moving them to carry the point of operation of the tool along the work, a correcting mechanism for differentially affecting the operation of said means, a hydraulic valve for controlling said correcting mechanism, a feeler mechanism for controlling said valve, said valve being constructed and arranged to cause normally a movement of the operating means in one direction, said movement being normally corrected by the feeler mechanism, and means for correcting said movement when the feeler mechanism is inoperative, said means being placed in and out of operation by the movement of the main starting lever to inoperative and operative position, respectively.

15 12. In a machine of the class described, a work holder, a tool holder, operating means for relatively moving them to carry the point of operation of the tool along the work, a correcting mechanism for differentially affecting the operation of said means, a hydraulic valve for controlling said correcting mechanism, a feeler mechanism for controlling said valve, said valve being constructed and arranged to leak slightly in one direction whereby a holder is moved toward a definite abnormal position, and a cam and connections between the valve and the holder whereby movement of the holder toward said abnormal position operates the valve to correct said movement, said cam and connections being automatically placed in control of the valve by the separation of the work and tool and placed out of control by approaching movement of the work and tool.

16 13. In a machine of the class described, a work holder, a tool holder, operating means for relatively moving them to carry the point of operation of the tool along the work, a correcting mechanism for differentially affecting the operation of said means,

a hydraulic valve for controlling said correcting mechanism, a work contacting mechanism for controlling said valve, said valve being constructed and arranged to leak slightly in one direction, whereby the correcting mechanism tends to move in a definite direction at all times, and a cam and connections between the valve and the correcting mechanism whereby said movement operates the valve to correct said movement. 70

14. In a machine of the class described, a work holder, a tool holder, operating means for relatively moving them to carry the point of operation of the tool along the work, a correcting mechanism for differentially affecting the operation of said means, a hydraulic valve for controlling said correcting mechanism, a feeler mechanism for controlling said valve, and a supplemental control mechanism connected to a movable element of the correcting mechanism for operating the valve in the absence of feeler control. 80

15. In a machine of the class described, a work holder, a tool holder, operating means for relatively moving them to carry the point of operation of the tool along the work, a correcting mechanism for differentially affecting the operation of said means, a hydraulic valve for controlling said correcting mechanism, a feeler mechanism for controlling said valve, a cam and connections between a movable element of the correcting mechanism and the valve for operating the valve in the absence of the feeler control, and means for rendering the cam inoperative as an incident of the commencement of operation on a work piece. 95

16. A machine of the class described having, in combination, an operating tool, means for guiding the relative movement of the tool and work, and correcting means including a feeler constructed and arranged continuously to engage a pattern surface, and means controlled thereby to maintain the tool in a predetermined angular relationship to the work, said last-named means being constructed and arranged, when the feeler is out of engagement with the pattern surface, to effect a relative movement of tool and work toward an extreme position, and a cam and connections, operated by said relative movement, to bring the tool and work back to a selected mean position, the connections providing for adjustment, 115 whereby the selected position may be varied. 120

17. A machine of the class described having, in combination, an operating tool, means for guiding the relative movement of the tool and work, and correcting means including a feeler constructed and arranged continuously to engage a pattern surface, and means controlled thereby to maintain the tool in a predetermined angular relationship to the work, and a cam and con- 125 130

nections, operated by abnormal relative movement between work and tool when the feeler is out of engagement with the pattern surface, to bring the tool and work back to an arbitrarily predeterminable mean position.

18. A machine of the class described, comprising means for sustaining the work and an operating tool, relatively movable to carry the point of operation progressively along the work, guiding means acting normally to determine the successive relative positions of said sustaining means and tool in combination with additional means controlled by the work for correcting or varying the effect of said guiding means, said additional means being constructed and arranged normally to move the guiding means to an abnormal position, said normal action being normally inhibited by the said work control, and a mechanism connecting the guiding means and the additional means to move the guiding means to a definite mean position when the work control is inoperative, said mechanism being adjustable to vary the definite position at will.

19. A machine of the class described, comprising means for sustaining the work and an operating tool, relatively movable to carry the point of operation progressively along the work, guiding means acting normally to determine the successive relative positions of said sustaining means and tool in combination with additional means controlled by the work for correcting or varying the effect of said guiding means, said additional means being constructed and arranged normally to move the guiding means to an extreme position, said normal action being normally inhibited by the said work control, and a mechanism comprising a cam and connections connecting the guiding means and the additional means to move the guiding means to a mean position when the work control is inoperative.

20. A machine of the class described, comprising a work support, an operating tool, means for moving said support and tool automatically with relation to each other, guiding means acting normally to determine approximately the relative position of said support and tool according to a desired contour of the work, in combination with correcting means engaging said contour for correcting or varying the operation of said guiding means, said correcting means being constructed and arranged normally to move the guiding means to an extreme position, said normal action being normally inhibited by the said work control, and a mechanism connecting the guiding means and the correcting means to move the guiding means to a mean position when the work control is inoperative.

21. A machine of the class described hav-

ing, in combination, a tool, a work support, means for producing relative movement of said tool and support to transfer the point of operation of the tool along the work, and correcting mechanism acting through said means to correct the angular relation of the tool and the work, said mechanism including a feeler engaging the work, and connections through which the mechanism is rendered active by variations in the position of the feeler as its point of engagement is transferred along the work, said correcting mechanism being constructed and arranged normally to vary the said angular relation to an extreme position upon cessation of the engagement between the feeler and the work, and a secondary correcting mechanism operated by movement toward said extreme position, for reversing such movement whereby said correcting mechanism is held balanced in the absence of the said feeler control.

22. A machine in which a tool is caused to operate progressively along the work, comprising means constructed and arranged to constrain the tool and work to assume successively predeterminable relative positions, in combination with work controlled mechanism which may be rendered active automatically to correct or vary the operation of said means, said work controlled mechanism comprising a hydraulic valve, and means independent of said work control for actuating the valve to balance leakage when the work control is inoperative.

23. In a machine of the class described, a work support, a tool constructed and arranged to operate upon the sole of a shoe, means including a feeler engaging a contour of the sole and hydraulically actuated mechanism controlled thereby for determining the relative position of sole and tool, said hydraulically actuated mechanism being constructed and arranged normally to determine an extreme relative position of the sole and tool when the feeler is not in operative position, and means comprising a valve and an actuating member therefor actuated by movement toward said extreme position to return the hydraulically actuated mechanism to a definite mean position.

24. A machine in which a tool is caused to operate upon work along a definite contour, having, in combination, a work support and an operating tool relatively movable, a guide, said support and guide being provided one with a cam groove and the other with guiding mechanism co-acting with the groove, and means for swinging the guide to maintain the desired relation between work and tool as the point of operation is transferred along the work, said means being provided with a hydraulic valve to control the guide, the guide and valve being

provided one with a cam and the other with a follower whereby movement to an extreme position is automatically corrected.

25. A machine of the class described, comprising a tool for operating progressively along work, power actuated means for moving the work with relation to the tool, and controlling means therefor comprising a pair of feelers arranged to bear against a pattern surface and by their movement with relation to each other to cause the operation of the power actuated means, said controlling means being constructed and arranged, when the feelers are removed from the pattern surface, to cause the operation of the power actuated means toward an abnormal position, and a mechanism actuated by the abnormal movement of the power actuated means constructed and arranged to move the controlling means to a predetermined position, whereby the power operated means is maintained at a corresponding predetermined position.

26. In a machine of the class described, a work support and an operating tool relatively movable in a plurality of directions, means for controlling the relative position of work and tool comprising a hydraulic cylinder and a piston therein, operative connections between the piston and the work support or tool, a valve controlling the movement of the piston, and a pair of feelers constructed and arranged to be moved with relation to each other through the varying contour of a pattern surface and thereby to shift the valve and correct the relative position of tool and work, and a member actuated by said piston movement and controlling said valve to return the piston and equalize leakage in the valve when not controlled by the feelers, when a definite arbitrarily predetermined position has been reached by the piston.

27. A machine in which a tool is caused to operate progressively along the work, comprising means constructed and arranged to constrain the tool and work to assume successively predetermined relative positions, in combination with pattern controlled mechanism which may be rendered active automatically to correct or vary the operation of said means, said mechanism being constructed and arranged to overcorrect constantly in the same direction, and a secondary correcting mechanism constructed and arranged to oppose said overcorrecting movement and to reverse and balance it at a predetermined point.

28. A machine of the class described, comprising in combination, a jack, a tool constructed and arranged to operate upon a shoe, means, including a feeler, engaging a contour of the sole of the shoe and fluid pressure actuated mechanism controlled by said means for determining the relative po-

sition of shoe and tool, said mechanism constructed and arranged to require constant correction in one direction, and a member actuated by movement of one of the shoe or tool to furnish a correction, when the feeler is inoperative to supply it, the magnitude of said correction being an increasing function of the movement of the said mechanism against the direction in which correction is required, whereby the mechanism will be arrested at a definite predetermined point.

29. In a machine of the class described, a shoe jack and a tool, automatic mechanism for transferring the point of operation of the tool over the shoe, a correcting mechanism for differentially affecting the operation of the automatic mechanism to maintain proper operative relation, comprising a pattern surface having a definite relation to the path of the tool over the work, a feeler co-operating with said pattern surface, a hydraulic control valve operated by said feeler, said valve being constructed and arranged to leak in one direction, whereby constant correction is required by said feeler, and an auxiliary correcting mechanism comprising a cam and connections operated by relative movement of the work and tool in obedience to said leakage to move the valve in a direction to increasingly offset the leakage as the correcting mechanism moves through a predetermined mean position whereby the correcting mechanism is balanced in that position.

30. In a machine of the class described, a shoe jack and a tool, automatic mechanism for transferring the point of operation of the tool over the shoe, a correcting mechanism for differentially affecting the operation of the automatic mechanism to maintain proper operative relation, comprising a pattern surface having a definite relation to the path of the tool over the work, a feeler co-operating with said pattern surface, a hydraulic control valve operated by said feeler, a member controlled by the valve to move the jack, one of the member and valve being provided with a cam and the other with a cam follower, whereby movement of the member from a normal position will operate the valve to correct the movement and determine a normal position for the jack, there being provision for adjustment in the mechanism between the member and the valve to vary the said normal position independently of the automatic operation of the machine.

31. In a machine of the class described, a shoe jack and a tool, automatic mechanism for transferring the point of operation of the tool over the shoe, a correcting mechanism for differentially affecting the operation of the automatic mechanism to maintain proper operative relation, comprising a pattern surface having a definite relation to

the path of the tool over the work, a feeler co-operating with said pattern surface, a hydraulic control valve operated by said feeler, a member controlled by the valve to move the jack, one of the member and valve being provided with a cam and the other with a cam follower, whereby movement of the member from a normal position will operate the valve to correct the movement and determine a normal position for the jack, the cam and follower being relatively adjustable to vary the position assumed by the member at the instant of balance.

32. In a machine of the class described, a shoe jack and a tool, automatic mechanism for transferring the point of operation of the tool over the shoe, a correcting mechanism for differentially affecting the operation of the automatic mechanism to maintain proper operative relation, comprising a pattern surface having a definite relation to the path of the tool over the work, a feeler co-operating with said pattern surface, a hydraulic control valve operated by said feeler, a member controlled by the valve to move the jack, one of the member and valve being provided with a cam and the other with a cam follower, whereby movement of the member from a normal position will operate the valve to correct the movement and determine a normal position for the jack, one of the cam and follower having a pivotal mounting, a lever supporting at one of its ends said pivotally mounted part, and another end of the lever being supported on the machine frame, and the fulcrum being adjustably mounted on the machine frame whereby the normal position defined by the corrective mechanism can be adjusted.

33. In a machine of the class described, a shoe jack and a tool, automatic mechanism for transferring the point of operation of the tool over the shoe, a correcting mechanism for differentially affecting the operation of the automatic mechanism to maintain proper operative relation, comprising a pattern surface having a definite relation to the path of the tool over the work, a feeler co-operating with said pattern surface, a hydraulic control valve operated by said feeler, a member controlled by the valve to move the jack, one of the member and valve being provided with a cam and the other with a cam follower, whereby movement of the member from a normal position will operate the valve to correct the movement and determine a normal position for the jack, the said pivotally mounted part when the machine is started.

34. In a machine of the class described, a shoe jack and a tool, automatic mechanism for transferring the point of operation of the tool over the shoe, a correcting mechanism for differentially affecting the operation of the automatic mechanism to maintain proper operative relation, comprising a pattern surface having a definite relation to the path of the tool over the work, a feeler co-operating with said pattern surface, a hydraulic control valve operated by said feeler, a member controlled by the valve to move the jack, one of the member and valve being provided with a cam and the other with a cam follower, whereby movement of the member from a normal position will operate the valve to correct the movement and determine a normal position for the jack, one of the cam and follower having a pivotal mounting, a lever supporting at one of its ends said pivotally mounted part, and another end of the lever being supported on the machine frame, and the fulcrum being adjustably mounted on the machine frame whereby the normal position defined by the corrective mechanism can be adjusted.

In testimony whereof I have signed my name to this specification.

FRANK BYCROFT KEALL.
